UNITED STATES PATENT OFFICE

JOHANNES MIERITZ, OF BERLIN, GERMANY

CUTTING DEVICE

Application filed December 5, 1930, Serial No. 500,358, and in Germany July 3, 1929.

This invention relates to a cutting device, which is intended first of all for the working of plates of wood, paste-board, sheet-metal, paper, and the like, and the arrangement and combination of its parts is such that not solely the outer edges of said plates can be worked, but also recesses and cut-outs of any desired shape can be produced in the face thereof. According to the invention the knife reciprocates like a ram and is driven by a motor firmly connected with the frame of the device, the frame having a base shiftable upon the plate to be provided with the cuts.

Preferably the armature of the motor which is an electric motor is immovably supported in the frame of the cutting device, whereas the stator of the motor that is combined with the magnet frame is rotatory and is connected with the reciprocating knife by suitable means, for instance and preferably by an eccentric drive. I attain by this arrangement that the mass of the combined stator and magnet frame acts as a fly mass, similar to a fly wheel, whereby unsteady operation of the knife is prevented. Without employment of a fly-mass the knife operates unsteadily because there is a considerable difference in the performance of the device between the downward or working stroke of the knife and the upward or idle stroke thereof. It is undoubtedly a great advantage that by arranging said members in the manner stated steady operation of the knife is attained without the provision of additional fly masses.

Furthermore, the present improvements present the possibility to produce vertical, as well as oblique or faceted cuts etc. with one and the same device, that is to say, cuts which are directed perpendicularly with respect to the face of the respective plate, or which are directed obliquely thereto, and for this purpose the knife and its driving means can be arranged at any desired angle with respect to the respective plate face.

The invention is illustrated diagrammatically and by way of example on the accompanying drawings on which Figure 1 is a side-view of a cutting device designed according to this invention; Figure 2 is a plan thereof; Figure 3 is a separate side-view solely of the

Referring to the first constructional form shown in Figs. 1-4, 1 denotes two vertical spaced semi-circular guide members firmly connected with brackets 3^a affixed to an annular base 3. The members 1 are connected with said brackets 3^a by the intermediary of short transverse members 1^a from which extend forth lateral grips 17, with the aid of which the entire device can be shifted in any direction upon the plate to be provided with the cut-outs or the like, as is more fully dealt with hereinafter.

The semi-circular members 1 serve as supports for a casing 4 in which are housed the stator 6 and the armature 5 of an electromotor; these parts 5 and 6 are supported by an axle 5^a, and the arrangement is such that the stator which is combined with the magnet frame is turnable whereas the armature is stationary. The rotatory stator is connected with an eccentric disc 7 which is encompassed by an eccentric ring 8, and from this ring extends downwardly a rod 9, to the free end of which the ram knife 11 is detachably attached. This rod is guided by a sleeve 10 extending forth from the casing 4.

The bottom face of the casing 4 is provided with shoulder-forming projections 12 which rest, and can slide along, upon the semi-circular members 1, and can be firmly connected therewith in any position of the casing 4 upon

them by means of clamping cheeks 13 and screws 14. The radius of the semicircle constituted by the members 1 corresponds to the distance between the working edge of the ram knife 11 and the bottom faces of the shoulders 12. Said working edge is located just over an aperture 16 provided in a transparent plate 15 consisting, for instance, of celluloid or cellon or the like and being firmly connected with the base ring 3. Whichever the position of the casing 4 with the electromotor and the parts 9, 10 and 11 upon or at the semi-circular members 1 may be, that is to say, perfectly independent of whether the ram knife stands vertically with respect to the plate 15 or forms any angle therewith, the working edge of the knife lies at any rate centrally over the opening 16.

The manner of operation of the device is as follows:

First of all the knife is adjusted over the plate 15 and its aperture 16 corresponding to the cuts to be produced, viz. whether they are to be vertical or oblique (faceted cuts). Then the casing 4 is secured in its position upon and at the semi-circular members 1. When now the current is switched on, the rotatory stator of the electromotor will rotate (the armature being stationary, as has already been described) and the knife will now be reciprocated by the eccentric members 7 and 8. Finally, the entire device is shifted upon the plate to be provided with the cuts, that plate having prior thereto been provided with lines indicating the cut-outs or recesses etc. to be produced, the device being so moved that the cutting edge of the knife passes along the respective line or lines which may be straight or curved in any way. The device is shifted upon the plate with the aid of the grips 17 which are provided for this purpose, as has already been mentioned at a preceding part of this specification. Owing to the provision of the transparent plate 16 the operator can distinctly see the line or lines to be followed, and the particles cut or severed off from the respective material are prevented from jumping upwardly and hindering the work.

As the stator of the motor with the magnet frame acts as a fly-mass, as already stated, the knife operates very uniformly which is very advantageous for the quality of the product and for guiding the apparatus.

In the modification illustrated in Figs. 5-7, 18 denotes a standard secured to a U-shaped base plate 19, the legs of which are provided with grips 20 located at the ends of the legs and serving for moving the device along upon the plate to be worked. The upper end of the standard 18 is curved in the direction to said grips and in it is supported a horizontal axle 22, one end of which is firmly connected with the casing 21 in which the motor is housed. The casing 21 can be turned together

with the axle 22, and these parts can be secured in their position by means of a screw 23 located upon the rear end of said axle which is suitably threaded.

From the casing 21 extends downwardly 70 the sleeve 21^a in which the reciprocating rod 24 holding the ram knife 25 is guided. This arrangement and combination of parts, including the motor and the eccentric members, is the same as in Figs. 3 and 4. In Fig. 5 75 the device is shown in a position in which vertical cut-outs will be produced. The knife is located over the space between the two legs of the U-shaped base plate. If faceted cut-outs are to be made, the screw 23 is 80 loosened and the casing 21 then turned to the desired angle, as, for instance, in Fig. 7, and for the knife rod 24 is substituted another knife rod 24^a of greater length than rod 24 so that the ram knife can act on the plate 85 upon which the device has been placed. The manner of operation is the same as with the first-described constructional form, and also in this case a transparent plate may be 90 attached to the base of the device and a slot will then be provided in said plate through which the knife can act upon the plate to be worked. In the position shown in Fig. 7, the casing with the knife has been turned laterally so much that the knife works outside the base plate, the facets produced being, 95 of course, correspondingly inclined.

In the further modification shown in Fig. 8 the casing 26 with its guide-sleeve 26^a and the rod 28 with the knife 27 are firmly connected with an arm 29 which is hinged at 31 to the base plate 30 from which extends upwardly a quadrant 32 that is provided with a scale along which the casing with the said 100 other members can be adjusted and can be secured in the adjusted position by suitable means. The manner of operation of this constructional form is the same as with the other constructional forms described in the preceding pages, and cut-outs or the like with 105 vertical, as well as with inclined or faceted edges can be produced.

Finally I have shown in Figs. 9-11 a constructional form intended solely for vertical cuts. The casing enclosing the electromotor 115 is practically the same as that in Figs. 1-4 and the same letters of reference as in those figures have been used also in Fig. 10 in so far as said casing etc. are concerned. The casing is supported on two vertical standards 120 33 projecting forth from a U-shaped base plate 34. This plate is shown separately in Fig. 11 which is a horizontal section in the plane XI-XI of Fig. 9. It will be obvious that also in this constructional form, as well 125 as in all other ones, the device works very uniformly and free from oscillations and shocks, as the rotary magnet frame acts as fly-mass, just as has fully been described 130 with respect to Figs. 1-4.

I wish it to be understood that I do not limit myself solely to the details of the various constructional forms of the cutting device or merely to these constructional forms which have been shown and described solely 5 by way of example. Many departures in the details are possible without departing from the gist of the invention. Thus, for instance, a crank drive may be substituted for the eccentric drive for the knife.

10 I claim:

11 1. A cutting device, comprising, in combination with a frame; an electromotor located in said frame and comprising a stationary armature and a rotary stator; a reciprocable rod; a ram knife at the free end of said rod; and means for converting the rotary motion of said stator into reciprocating motion and for transmitting this motion to the 15 said rod and knife.

20 2. A cutting device, comprising, in combination with a frame; an electromotor located in said frame and comprising a stationary armature and a rotary stator; a reciprocable rod; a ram knife at the free end of said rod; an eccentric disk connected with said stator, and an eccentric ring encompassing said disk and being connected with said rod so as to convert the rotary motion of the 25 said stator into reciprocating motion and to transmit this latter to the said rod and knife.

30 3. A cutting device, comprising, in combination with a frame; a casing supported by the same and being so attached to it that it can be adjusted to various angular positions; an electromotor located in said casing and comprising a stationary armature and a rotary stator; a reciprocable rod attached to said casing; a ram knife at the free end of 35 said rod; and means for converting the rotary motion of said stator into reciprocating motion and for transmitting this motion to the said rod and knife.

40 4. A cutting device, comprising, in combination, a vertical semi-circular frame; a reciprocable rod being so attached to said frame as to be adapted to be adjusted along it to various angular positions; a ram knife attached to the free end of said rod; and 45 means for reciprocating this latter with its knife.

50 5. A cutting device, comprising, in combination, a vertical semi-circular frame; an annular base plate to which said frame is affixed; a reciprocable rod being so attached to said frame as to be adapted to be adjusted along it to various angular positions; a ram knife attached to the free end of said rod; and means for reciprocating this latter with 55 its knife.

60 6. A cutting device, comprising, in combination, a vertical semi-circular frame; an annular base plate to which said frame is affixed; a transparent plate closing the free space of said base plate and having a central

aperture; a reciprocable rod being so attached to said frame as to be adapted to be adjusted along it to various angular positions; a ram knife attached to the free end of said rod; and means for reciprocating this 70 latter with its knife.

7. A cutting device, comprising, in combination, an upwardly extending arm adapted to be turned into various angular positions and to be fixed in every one thereof; a casing 75 connected with said arm; an electromotor arranged in said casing; a reciprocable rod attached to said casing; a ram knife attached to the free end of said rod; and means for converting the rotary motion of said stator into 80 reciprocating motion and for transmitting this motion to the said rod and knife.

8. A cutting device, comprising, in combination, an upwardly extending arm adapted to be turned into various angular positions and to be fixed in every one thereof; a circularly curved guide member for said arm; a casing connected with said arm; an electromotor arranged in said casing; a reciprocable rod attached to said casing; a ram 90 knife attached to the free end of said rod; and means for converting the rotary motion of said motor into reciprocating motion and for transmitting this motion to the said rod and knife.

9. A cutting device, comprising, in combination a frame; a reciprocable rod extending forth from the same; a ram knife attached to the free end of said rod; and means for reciprocating the said rod with its knife; 100 a base plate carrying said frame and having a recess, a transparent plate closing said recess and having an aperture through which said knife is moved.

In testimony whereof I affix my signature. 105
JOHANNES MIERITZ.
